UNITED STATES PATENT OFFICE

WILLIAM AUSTIN JACKSON, OF HAMILTON, ONTARIO, CANADA, ASSIGNOR TO THE CANADIAN COLORTYPE, LIMITED, OF HAMILTON, ONTARIO, CANADA, A CORPORATION OF ONTARIO

DOOR ACTUATING AND RETAINING MECHANISM

Application filed May 28, 1930. Serial No. 456,587.

My invention relates to improvements in mechanisms for simultaneously opening double doors and retaining them in the open position, and my invention is particularly designed for double garage doors and the like in which it is desired to always open both doors and to retain such doors in the open position against slamming under the force of the wind or from any other cause. A further object of my invention is to devise a simple mechanism which can be readily applied to any pair of doors without making any alterations in the doors themselves or in the door frame, and a still further object of my invention is to construct such a device which is readily operated by means of a movable handle positioned upon the exterior of one of the doors and which can be operated with very little more exertion than lifting the latch of a standard swingable latch door lock.

My invention consists of a door actuating and retaining mechanism constructed and arranged all as hereinafter described and illustrated in the accompanying drawings in which:—

Figure 1 is a front elevational view of a garage, the double doors thereof being open.

Figure 2 is a plan view thereof, a fragmentary portion of the garage being shown.

Figure 3 is an enlarged perspective view of a portion of my mechanism and a fragmentary portion of the garage and one door, the mechanism being broken away intermediate of its length.

Figure 4 is a perspective view of a fragmentary portion of my mechanism mounted upon a fragmentary portion of the garage door.

Figure 5 is a further enlarged view of a fragmentary portion of my mechanism partly in section, and

Figure 6 is a side elevational view of the latch bar engaging plate of my mechanism, the latch bar being shown in engagement

therein in full lines and disengaged in dotted lines.

Like characters of reference indicate corresponding parts in the different views in the drawings.

The garage 1 illustrated in Fig. 1 is of the standard type furnished with a pair of outwardly swinging doors 2 and 3 which swing from the closed position into the open position as clearly shown in Fig. 2. My mechanism is so designed that its major portion is secured upon one door, and as illustrated in the drawings I have shown such major portion mounted upon the door 2. Upon the upper portion of the inner batten 4 of the door 2 I mount a bracket 5 which is secured to the door by bolts or screws. Upon reference to Figures 1 and 3 it will be seen that this bracket extends from the open door 2 to substantially the centre of the doorway. The bracket members are preferably formed of angle irons.

A latch bar member 6 extends from the vicinity of the outer upper corner of the door 2 to the vicinity of the outer end of the bracket 5, the inner end of the latch bar being loosely supported upon the bracket as illustrated in Fig. 5 for oscillation substantially about the longitudinal axis of the bar as will hereinafter appear.

The ends 7 and 8 of the latch bar 6 are bent along the horizontal plane of the bar so that the end 7 lies substantially parallel to the door 2 and the end 8 substantially parallel to the horizontal member 9 of the door frame when the door is fully open.

The end 7 of the latch bar 6 is pivotally secured to the door by means of an angularly inclined lug 10 which extends from the end 7 intermediately of its length and pivotally connected to the angularly inclined bracket 11 which is secured to the inner face of the door 2. A bolt or pin 12 extends through the lug 10 and bracket 11 whereby a pivotal connection is formed. The angularity of the

lug 10 and the bracket 11 is such that they extend substantially at right angles to an imaginary line extending from the centre of the bolt 12 to the centre of the rockable connection between the inner end of the latch bar 6 and the bracket 5 illustrated in Fig. 5. In forming the rockable connection illustrated in Fig. 5 I drill a pair of holes 13 and 14 in the latch bar 6 and bracket 5 and loosely 10 position a connecting bolt 15 therein, the bolt being of less diameter than the holes. Upon the bolt 15 and between the latch bar 6 and bracket 5 I furnish a convex faced washer 16 so that the latch bar 6 may readily oscillate upon the bracket 5.

In the vicinity of the centre of the lower face of the door frame member 9 I position a downwardly extending keeper plate 17 which is suitably secured to the member 9; 20 it being understood that the doors contact with the side 18 of the member 9 so that the plate 17 does not in any way interfere with the shutting of the doors. This plate 17 is formed with a centrally positioned upwardly extending slot 19, the rear portion 20 of the plate being of less depth than the front portion 21. The portions 20 and 21 have sloped edges 22 as illustrated in Fig. 6 so that the upper edges 23 of the members 7 30 and 8 slide thereon into the slot 19 when the doors are swung fully open or shut as shall be hereinafter explained.

In the vicinity of the center of the outer vertical edge 24 of the door 2 I pivotally 35 mount a horizontal lever 25 having a handle 26 formed upon its outer end, the lever being recessed into the edge of the door so that it does not come into contact with the edge 27 of the door 3 preventing the doors fully 40 closing. The inner end of the lever 25 is connected by means of a chain 28 to the outer extremity of the end 7 of the latch bar 6.

The door 3 is furnished with a bracket 29 secured to the outer upper corner of its inner 45 face, and 30 is a bar pivotally connected to the bracket 29 and extending into pivotal connection with the outer end of the bracket 5, a pin or bolt 31 extending through orifices in the bar 30 and bracket 5 to form the pivotal connection. The inner end of the bar 30 is provided with a plurality of bolt or pin receiving 50 orifices whereby the opening of the door 3 may be adjusted when my mechanism is being installed.

55 The operation of my invention is as follows:—

When the garage doors are closed the mechanism is in the position illustrated in dotted lines in Fig. 2, wherein the edge 23 of the 60 outer end 7 of the latch bar is contained in the slot 19 in keeper plate 17, thus retaining the doors and mechanism from swinging outwardly. The respective lengths of the bracket 5 and bar 30 are so arranged that the 65 door 3 completely closes in swinging the

bracket and bar rearwardly. When it is desired to open the doors the handle 26 is grasped and moved upwardly thus pulling the chain 28 and oscillating the latch bar 6 to swing its end 7 downwardly out of engagement with the slot in the keeper plate 17 which permits the door 2 to be swung outwardly. When the bracket 5 swings from the position illustrated in dotted lines into the position illustrated in full lines in Fig. 2 the bar 30 70 will be swung from the position illustrated in dotted lines into the position illustrated in full lines thus opening the door 3 at the same time.

As the latch bar 6 is carried by the door 2 and bracket 5, the latch bar will also swing outwardly from the position illustrated in dotted lines into the position illustrated in full lines wherein its inner bent end will engage the edge 22 of the plate 17 as the doors 80 approach their fully open position.

As hereinbefore explained the latch bar 6 is loosely mounted upon the bracket 5 and pivotally secured to the door 2 so that it is capable of an oscillating movement permitting the bent ends 7 and 8 to swing downwardly in unison as indicated by the arrows 90 in Fig. 3.

It will be therefore appreciated that when the edge 23 of the end 8 comes into contact with the sloped edge 22 of the plate 17 that such end 8 will swing downwardly and travel along the plate edge 22 until it reaches the upwardly extending slot 19 when its edge 23 will move upwardly into the slot as the bar 6 100 restores itself to its normal position under the force of gravity; it being understood upon reference to Fig. 2 that the major portion of the bar 6 is lifted up when its ends 7 and 8 are depressed and as the weight of such lifted portion of the bar 6 is greater than the combined weight of the depressed ends that the bar will restore itself to its normal position when the ends are released or permitted to swing upwardly. If this action through 105 gravity is not fast enough a spring 32 may be utilized, such spring extending downwardly from the bar 6 to the door 2.

When the end 8 of the bar 6 enters the slot 19 in the plate 17 the bar 6 is of course 115 retained against further movement in either direction which therefore locks the door 2 in the open position, and as the door 3 is connected to the bracket 5 by means of the bar 30 it will also be held in the open position.

When it is desired to close the doors the outer end of the lever 25 is swung upwardly by means of the handle 26 so that its inner end moves downwardly pulling the chain 28 and swinging the latch bar ends 7 and 8 downwardly which moves the edge 23 of the end 8 out of the slot 19 in the plate 17, thus permitting the latch bar to be swung inwardly and the doors closed.

From the foregoing description it will be

apparent that I have devised a particularly simple and effective type of door actuating and retaining mechanism which can be cheaply manufactured and readily installed, and although I have shown and described a particular embodiment of my invention it is to be understood that I can make such changes and alterations as I may from time to time deem necessary without departing from the spirit of my invention as set forth in the appended claims.

What I claim as my invention is:

1. In a door actuating and retaining mechanism, a latch bar pivotally supported by the door and oscillatable through a vertical plane substantially transverse to its length, inclined ends formed upon the bar, the outer end lying substantially parallel to the inner face of the door and the inner end lying substantially parallel to the horizontal portion of the doorway when the door is fully opened, and a keeper plate secured to the upper portion of the doorway with which the inclined ends of the latch bar detachably engage.
2. In a door actuating and retaining mechanism, a latch bar solely supported by the door and oscillatable through a vertical plane substantially transverse to its length, inclined ends formed upon the bar, the outer end lying substantially parallel to the inner face of the door and the inner end lying substantially parallel to the horizontal portion of the doorway when the door is fully opened, a bracket member extending from the inner face of the door and upon which the inner end of the latch bar is oscillatably mounted, a pivotal connection between the door and the outer inclined end of the bar, said pivotal connection extending substantially at right angles to an imaginary line extending from the oscillatable connection between the latch bar and the bracket and the pivotal connection between the door and the inclined end of the latch bar, and a downwardly extending keeper plate secured to the upper portion of the doorway and with which the both ends of the latch detachably engage.
3. In a door actuating and retaining mechanism, a latch bar oscillatable substantially about its longitudinal axis and solely supported by the door in inclined relation to its inner face, a pair of latch bar supporting members secured to the door and upon which the latch bar is oscillatably mounted, inclined ends formed upon the bar, the outer end lying substantially parallel to the inner face of the door and the inner end lying substantially parallel to the horizontal portion of the doorway when the door is fully opened, and a keeper plate secured to the upper portion of the doorway and with which the outer ends of the latch bar detachably engage to retain the door in either the open or closed position.
4. In a door actuating and retaining mech-

anism for double doors, a latch bar solely supported by one door and oscillatable substantially about its longitudinal axis, a latch bar supporting member extending from said door a bar forming a pivotal connection between the other door and the latch bar supporting member, and a keeper plate secured to the upper portion of the doorway, and means upon the inner end of the latch bar detachably engaging the keeper plate.
